UNITED STATES PATENT OFFICE.

RICHARD F. PREUSSER, OF WASHINGTON, DISTRICT OF COLUMBIA.

CAR-FENDER.

SPECIFICATION forming part of Letters Patent No. 650,762, dated May 29, 1900.

Application filed December 23, 1899. Serial No. 741,425. (No model.)

To all whom it may concern:

Be it known that I, RICHARD F. PREUSSER, a citizen of the United States, residing at Washington, in the District of Columbia, have 5 invented certain new and useful Improvements in Car-Fenders; and I do hereby declare the following to be a full, clear, and exact description of the invention, such as will enable others skilled in the art to which it 10 appertains to make and use the same.

The object is to present a car-fender which shall be light and simple of construction and capable of attachment to and detachment from cars of general construction, which shall 15 be readily responsive to pressure to cause it to be projected into such relation to the road-bed as to pick up an object struck, and which when not in use may be folded back against the dashboard of a car, and thus be out of 20 the way of the coupler; furthermore, to present a combined fender and wheel-guard, the two devices being connected in such manner as to be adapted at the same time and with rapidity, ease, and certainty of operation 25 to be brought into position for use.

The invention consists in the novel construction of a wheel-guard and of a combined wheel-guard and fender, as will be hereinafter fully described.

30 In the accompanying drawings, forming a part of this specification, and in which like letters of reference indicate corresponding parts, Figure 1 is a view in perspective displaying the front portion of a street-car equipped with the fender. Fig. 2 is a similar view showing a car equipped with a combined fender and wheel-guard. Fig. 3 is a view in elevation, partly in section, displaying the connection between the parts of the two devices, the section being taken to one side of 35 the fender. Fig. 4 is a perspective detail view of the fender and wheel-guard-operating shaft. Fig. 5 is a detail view displaying a modified form of hanger.

40 Referring to the drawings, A designates the fender, and B the wheel-guard.

The fender-frame is constructed of two arms or side pieces a , rendered rigid by a cross-bar a^2 , connecting the outer portions of 45 the arms, the bar for lightness and from a standpoint of economy being constructed tubular, although, if preferred, it may be made

of a solid bar of metal. In the form herein shown the bar carries two T-shaped joints a^3 , which support the arms a , the latter by preference being also of tubular metal. Each fender-arm is straight, or practically so, and is provided at its rear end with two friction-rollers a^4 , adapted to bear upon the hanger-arms C, hereinafter to be described, whereby 55 friction between these parts will be reduced to a minimum. Upon each arm is placed a coiled spring a^5 , the terminal coil of one end bearing against the hanger C and the terminal coil of the other end being secured to the 60 arm, as by being passed through an opening therein. (Clearly shown in Fig. 3.) While the general shape of the arms and the arrangement of the springs as herein shown is that which will usually be preferred, it is to be 65 understood that the invention is not to be limited to this precise construction, as other designs may be employed without departing from the spirit thereof.

Secured to the cross-bar a^2 are two forward-projecting arms a^6 , constituting the sides of a scoop, these arms being connected and rendered rigid by cross-bars a^7 and a^8 , the front bar a^8 being by preference solid in order to present the greatest resistance to bending or 80 buckling, and the bar a^7 being by preference tubular for the sake of lightness, and in order that the front bar may further be braced against bending or buckling, as by contact with an obstruction, brace plates or bars a^9 85 are employed, the same being provided with recesses, in which rest the bars a^2 a^7 a^8 , the recesses for the bars a^2 and a^8 being in the ends of the plates and those for the bar a^7 on the under side of the plates. It is to be understood that instead of employing recesses for the purpose described the plates may be provided with openings to be engaged by the bars. The floor of the scoop is constructed, 90 preferably, of a series of thin metallic strips 95 secured in any suitable manner to the bars a^2 and a^8 .

To limit the downward movement of the fender and at the same time to prevent injury that would occur by the scoop coming 100 into contact with the road-bed, the bar a^7 is provided with rollers to contact with the road-bed.

The net a^{10} may be made of any suitable

material, in this instance of connected links, or of links and plates, the net being connected at its bottom to the bar a^3 and at its sides to chains a^{11} . At its upper side the net is 5 connected to the top bar a^{12} , having its ends bent upon themselves to form loops a^{13} , in which the upper links of the chains a^{11} are confined, and then at right angles to said loops to form pintles a^{14} , by which the fender 10 is held in operative position, as will presently appear.

As a means for supporting the fender in position for operation two hangers C are employed, these being securely bolted to the under side of the car-floor, as clearly shown in 15 Fig. 3. To facilitate removal of the hanger from the car should the hanger become damaged, the upper end of each hanger is formed with a dovetailed or undercut projection c , 20 which engages with a plate c^2 , provided with a dovetailed groove, the plate being secured to the under side of the car, and through the projection and the plate passes a bolt c^3 , by which the parts are held assembled in connection 25 with the bottom of the car. The hangers are by preference made of a strong resilient metal, such as boiler-steel, and each is formed at its bottom into a forward-and-rearward-curved hook, in the loop of which 30 work the rollers a^4 , the lower end of the hook being slotted to receive the side arms a . Thus when pressure is applied to the scoop, as when an object is struck, the friction-rollers will move back on the lower curved portion 35 of the hooks and will by the springs a^5 be cushioned, so that the force of the blow will be lessened. This arrangement of supporting the fender from the hangers presents points of advantage in the simplicity of its 40 construction and also in the readiness with which the fender may be detached from the hanger when necessary.

Near the upper portion of each hanger is located a pair of lugs or bosses c^4 , between 45 which is pivoted a bracket c^5 , each bracket at its lower end being provided with a toe or projection c^6 , which extends through a slot provided in the hanger for the purpose, so that the movement of the bracket is limited 50 by contact of the toe with the upper wall of such slot. The brackets are thus adapted for movement in a circumscribed arc, their rearward movement being limited by contact with the face of the hangers and their forward 55 movement by contact of the toe c^6 with the wall of the slot. It is to be understood that I do not limit myself to the precise manner of mounting the brackets, as other arrangements may be employed without departing 60 from the spirit of the invention.

Supported by hangers d , secured to the under side of the car-floor, is a transverse shaft E , which carries two levers e^2 , secured to the under side of the shaft and inclining downward and forward toward the front of the fender, and two levers e^3 , which are secured to the upper side of the shaft and are inclined

upward and rearward away from the fender, the two pairs of levers being set on the shaft at such distance apart as to bring them into alignment for proper connection with the fender and wheel-guard. The shaft E is by preference rectangular in cross-section and has its end formed into pintles to work in bearings formed in the hangers d . To the lower portion of each lever e^2 is secured one end of a chain a^{15} , the other end of which is connected with the cross-bar a^7 , as by a hook. To the upper ends of the levers e^3 are pivotally connected links b , the free ends of which 80 are similarly connected to the side arms b^2 of the wheel-guard B . This guard comprises in this instance two cross-bars b^3 b^4 , the former of which is mounted in bearings formed in brackets b^5 , suitably supported from the 85 car, both of the bars b^3 and b^4 being secured in any desired manner to the side arms b^2 . The bars are connected, preferably, by resilient metallic strips b^6 , forming the scoop, although other materials may be employed in 90 lieu of the strips.

It will be observed that the upper and longer portion of the side arms b^2 are curved or inclined away from the bar b^3 , which constitutes the pivotal point of the guard, so that 95 the bulk of the weight of these arms being to one side of the bar b^3 they will act adjunctively with the springs a^4 on the fender to keep the guard at the proper distance above the track.

Secured to the shaft E is an arm e^4 , the free end of which is provided with a slot, in which works the lower end of a foot-lever F , the upper end of which projects above the floor of the car adjacent to the dashboard and has a 105 head f , by which the lever may be depressed. Journaled on the foot-lever above the arm are two friction-rollers f^2 , (only one being shown and indicated in dotted lines,) which bear upon the arm on each side of the slot, 110 and below the arm is a stop-pin f^3 , which serves to hold the arm against separation from the lever.

It will be seen that when pressure is applied to the foot-lever the shaft E will be 115 rocked, thus drawing the levers e^3 backward and projecting the fender downward into operative engagement with the road-bed and the levers e^2 forward and in like manner projecting the wheel-guard down into operative 120 position with the road-bed.

The device thus far described is a combined fender and wheel-guard; but, as shown in Fig. 2, the wheel-guard may be dispensed with and the fender alone used. When this 125 arrangement is adopted, it will only be necessary to detach the link b and levers e^3 and remove the wheel-guard, or, if the car be constructed without the wheel-guard, then the levers e^3 will be omitted.

Instead of employing the form of hanger shown in Figs. 1, 2, and 3—that is, one in which the fender-supporting hook curves toward the rear of the car—I may, as shown in

Fig. 5, employ a hanger the supporting-hook of which curves toward the front of the car, the advantage of this latter form of hanger residing in the fact that the fender may readily be lifted out of engagement therewith without requiring detachment of the hangers from the car, which will be necessary when the form of hanger shown in Figs. 1, 2, and 3 is employed. It is also to be understood 10 that instead of having the chains a^{15} pass over the rod a^3 and hook into engagement with the cross-bar a^7 , and thus over the scoop, they may pass under the scoop and be hooked into engagement with the cross-bar a^7 . It will be 15 observed that the arc of movement of the outer ends of the chains a^{15} is concentric with the lower ends of the levers e^2 , so that in lifting the fender to fold it back against the dashboard it will not be necessary to detach 20 the chains from the scoop, as would be necessary if the two parts moved in different arcs.

Having thus fully described my invention, what I claim as new, and desire to secure by Letters Patent, is—

- 25 1. The combination with a car-fender, of hangers provided with curved, bifurcated projections, fender-arms having friction-rollers to engage the said projections, brackets pivotally connected with the hangers, and having a circumscribed arc of movement, and chains connecting the brackets and the fender, substantially as described.
2. The combination with a car-fender, of hangers provided with forward-extending 30 curved, bifurcated projections, fender-arms having friction-rollers to engage the said projections, brackets pivotally connected with the hangers, and having a circumscribed arc

of movement, and chains connecting the brackets and the fender, substantially as described. 40

3. The combination with a car-fender, of hangers provided with rearward-extending dovetailed or undercut projections, and forward-extending curved bifurcated projections, fender-arms having friction-rollers to engage the said latter projections, brackets pivotally connected with the hangers, and having a circumscribed arc of movement, chains connecting the brackets and the fender, plates secured to the under side of the car, and having dovetailed or undercut grooves to be engaged by the rearward-extending projections of the hangers, and means for holding the hangers and the plates assembled, substantially as described. 45 50 55

4. In a car-fender, hangers provided with curved projections, fender-supporting arms having friction-rollers to engage the projections, a rock-shaft carrying-levers and means 60 for actuating the rock-shaft, and chains connecting the lower ends of the levers and the front portion of the fender, the arc of movement of the outer ends of the chains being concentric with the lower ends of the levers, 65 whereby, in lifting the fender to fold it back against the dashboard of a car, it will not be necessary to disconnect the chains from the fender, substantially as described.

In testimony whereof I affix my signature 70 in the presence of two subscribing witnesses.
